UNITED STATES PATENT OFFICE.

THOMAS WOLLWORTH, OF CINCINNATI, OHIO.

SMOOTHING-IRON.

SPECIFICATION forming part of Letters Patent No. 369,830, dated September 13, 1887.

Application filed February 8, 1886. Serial No. 191,150. (Model.)

To all whom it may concern:

Be it known that I, THOMAS WOLLWORTH, a resident of Cincinnati, in the county of Hamilton and State of Ohio, have invented certain 5 new and useful Improvements in Smoothing-Irons, of which the following is a specification.

The object of my invention is to provide an iron which shall retain its heat by means of an internal heating apparatus. This object I 10 attain by the use of a hollow reversible iron.

In the accompanying drawings, Figure 1 is a side elevation of my improved iron. Fig. 2 may be termed a rear elevation of the same. Fig. 3 is a perspective view showing the un- 15

derside of the detachable top. Fig. 4 is a perspective view of the iron with the handle and detachable top removed. Fig. 5 is a central longitudinal section of the iron. Fig. 6 is a perspective view of the burner. Fig. 7 is a 20 perspective view of the burner-holder.

The box or body A is in shape preferably that of the ordinary iron, but deeper, to accommodate the internal heating apparatus. This body is provided with two flat ironing- 25 surfaces, a' , whose faces are smoothly polished. The sides a' are provided with orifices a^3 sufficient in size and number to admit the requisite amount of air. Around the edge of each flat surface a ridge, B, projects, and immediately 30 under this ridge, for the purpose of increasing it, there are preferably cut the grooves b .

The plate C (shown in Fig. 3) is provided on each side with a flange-hook, C' C². The handle D is attached to the plate C in any convenient manner, but preferably as shown in 35 Fig. 3. This plate C is attached to the box or body A in the manner shown in Figs. 1 and 2, the hook C' engaging under the ridge B and forming a firm attachment of the handle 40 through the medium of plate C to the iron proper. The plate C is prevented from slipping off the body A by the pin D', which is dropped through the opening C³ in plate C, into the opening a^4 in the top of the body A.

45 The burner-holder (shown in Fig. 7) consists of a hollow cylinder, E', provided at one end with the annular flange E². Two longitudinal openings, e, are cut opposite each other in the cylinder E'. The flange E² is provided with 50 two openings, e², through which screws pass

to retain the holder in position in the iron or body A. A hook, e', projects from the face of the flange E², as shown in Fig. 7, to retain the catch h, and in turn the burner in position.

The burner F (shown in Fig. 6) is a hollow 55 cylinder having opposite slots, f, cut in it corresponding to the openings e in the holder E. The burner F is filled with some porous material, such as asbestos, among non-combustible substances, and wicking among combustible 60 substances. Asbestos is the preferred material. This absorbent material G absorbs and retains the burning composition which I employ.

The end of the burner F is provided with 65 some form of handle or catch, a convenient combination of both being shown in Figs. 2, 4, and 6. A strip of metal is bent to form the handle H, and one end prolonged to form the catch h. The burner F is placed in the holder 70 E and turned until the catch h rests in the hook e'. The openings f then coincide with the openings e, as shown in Fig. 5. The holder E is held in position in the body A by the screws m, which pass through openings e² into the end 75 of the body. The end of the body A is provided with two sets of screw-holes, so that the holder E may be held in another position, if so desired.

When the burner is lighted and occupies the 80 position shown in the drawings, it of course serves to keep the whole iron hot; but the upper surface is heated more than the lower one, and when an extra hot iron is required the handle D and plate C are detached, the iron 85 turned over, and the handle and plate are then attached to the other flat surface through the medium of the flanges B and C' C². By this manner the hot side is turned down.

When it is desired to have a full heat, the 90 position of the burner in relation to the holder will be that shown in Figs. 6 and 7; but when it is desired to turn off a portion of the heat the burner is turned in the holder by means of the handle H to any desired position, so that 95 either one-third ($\frac{1}{3}$) or one-fourth, ($\frac{1}{4}$), as desired, of the openings f will be exposed to the openings e in holder E.

The advantages of such an iron are obvious. It presents two smoothing-surfaces, one of 100

which is heating while the other is cooling. Having the fire within it, (like the old tailor's goose,) it keeps warm for a long time, and may be used continuously for a long time.

5 The combustible material which I employ is preferably of such a kind that, while it produces a heat, it at the same time gives off little or no smoke or smell, and is very cheap.

While the various features of my invention 10 are preferably employed together, one or more of said features may be used without the remainder, and in so far as applicable one or more of said features may be used in connection with irons other than of the description 15 herein specifically described.

What I claim as new, and desire to secure by Letters Patent, is—

1. In combination with a two-faced reversible smoothing-iron, the burner - holder E', 20 having hook e', and detachable burner F, having slot or slots f, as and for the purposes set forth.

2. A two-faced reversible smoothing-iron, having grooves b on both sides and near the smoothing-surfaces, in combination with plate 25 C, having hooked flanges C' C², and handle D, substantially as and for the purposes set forth.

3. In a self-heating reversible iron, the combination of burner-holder E', having flange E², hook e', and slot or slots e, and burner F, having handle H, and slot or slots f, substantially as set forth.

4. A two-faced reversible smoothing-iron having grooves b on both sides and near the smoothing-surfaces, plate C, having hooked 35 flanges C' C², and handle D, and the detachable burner and holder, substantially as set forth.

THOMAS WOLLWORTH.
